UNITED STATES PATENT OFFICE.

LOUIS J. PETERS, OF BROOKLYN, NEW YORK.

MATCH-COMB.

1,330,279.

Specification of Letters Patent. Patented Feb. 10, 1920.

Application filed January 21, 1919. Serial No. 272,385.

To all whom it may concern:

Be it known that I, LOUIS J. PETERS, a citizen of the United States, residing at Brooklyn, in the county of Kings and State 5 of New York, have invented new and useful Improvements in Match-Combs, of which the following is a specification.

This invention relates to improvements in matches, and more particularly to the type 10 of match construction known as strip or comb matches.

This type of match is generally utilized in covered form—known as a “book match” in the trade—the book being made up of 15 the comb or strip, and the cover within which the comb is secured by stapling through the base portion of the comb.

The present invention pertains more specifically to the formation of the comb or 20 strip element which is generally formed from a strip of suitable paper board, the latter being subjected to suitable die action which not only serves to produce a slotted or severed effect extending inwardly from a 25 side edge of the strip toward the opposite edge—forming the embryo structure or splint of the individual match—but also tends to produce an offset relation between adjacent splints, the inner ends of the 30 splints each remaining attached to the unsevered portion of the strip. These splints are generally formed in units of a predetermined number of splints—ten, for instance—and these units may be spaced apart 35 in the length of the stock strip by removing the splint portion between the units, the strip thus being formed of a succession of units of this general type.

The strip is then dipped to complete the 40 match, and may be scored on a line approximating the inner ends of the splints, thus producing a comb effect—the source of the trade name. The units are then separated, and finally incased to produce the book.

Obviously, the successful production of 45 the comb is more or less dependent on the character of the slit-producing or severing operation, since the embryo structure or splint—made up of paper stock—is liable 50 to be weakened by the severing and offsetting action. Hence, the die operations are of a more or less intricate type.

While the book or comb match structures 55 have gone into extensive commercial use—owing to the low cost of manufacture—they have the disadvantage of inherent weakness

due to the fact that each match has its splint portion formed from a single thickness of the stock and has been subjected to the severing and offsetting operation, and in addition, may be presented by a flaw or variation in character of the strip stock itself.

Hence, even with the best type of die operation and careful manipulation in the formation of the comb, one or more of the 65 individual matches of the comb may be so weakened as to be unable to withstand the pressures developed in manipulating the match to ignite it. And in addition, this weakness may be accentuated, by more or 70 less careless handling in detaching the match from its comb.

As a result, it frequently happens that the splint may break at the base of the head or at an intermediate portion of its length, 75 and while the break may not separate the head portion from the part retained in the fingers—and even this may occur occasionally—the break causes a bend to the ignited portion of the match such as to produce 80 great inconvenience and frequently results in burning the fingers.

The present invention is designed to greatly reduce if not eliminate the effects 85 of this weakness by providing a structural strengthening factor in the match itself by producing a rib-like formation to the splint portion, preferably in advance of the offsetting operation, for instance, during the action of the dies, so that this strengthening 90 factor is present in the completed comb, but its presence tends to decrease the liability of a damaging effect during the dieing operation and thereby reducing the weakening tendency in the completed match. 95

This formation is of any preferred type, a simple way being to form a depression on one side of the strip, the displaced material forming a rib on the other side, thus varying the cross-section of the splint by a more 100 or less off-set relation of an intermediate portion of the splint with the offset extending in the direction of splint length. This splint offset may extend throughout the length of the splint or for a portion of such 105 length. Since this rib-like formation is preferably provided during and as a part of the dieing operation, the manufacturing cost of the comb is not materially affected.

To these and other ends, therefore, the 110 nature of which will be readily understood as the invention is hereinafter disclosed,

said invention consists in the improved construction and combination of parts herein-after fully described, illustrated in the accompanying drawings and more particu-
5 larly pointed out in the appended claims.

In the accompanying drawings, in which similar reference characters indicate similar parts in each of the views,—

Figure 1 is a perspective view of a comb
10 strip in its form preliminary to the dipping operation.

Fig. 2 is a perspective view of a completed comb.

Fig. 3 is a cross-sectional view of an in-
15 dividual match.

Fig. 4 is a plan view partly in section showing a modified form.

Since the present invention pertains more particularly to the product, I have not illus-
20 trated the detail method of manufacture, excepting that I have shown an embodiment of embryo comb formation to more clearly point out the general principles. It may be noted, however, that the comb strip of Fig.
25 1 is initially in the form of a strip of paper board of suitable character, the width of which practically corresponds to that of the base strip 10 plus the length of the splints of the matches, the length of the strip not
30 being considered, since the die operations serve to remove portions of the strip (indicated by spaces 11) and thus form individual combs.

In prior practice, the die operations also
35 serve to divide the spaced portions into the individual splints 12, through a severing action, extending from one side edge inwardly in directions transverse to the strip length. During the operations there is pro-
40 vided an off-setting operation—which may be termed group offsetting—by means of which adjacent splints are offset with relation to each other, alternate splints extend-
45 ing in the same general plane, thus provid-
ing practically two groups of splints, the planes of the outer ends of the two groups being spaced apart, while the inner ends—
integral with strip 10—are in the same plane.

50 As heretofore pointed out, the character of die operation is of importance since the severing and off-setting action may tend to weaken the splint.

Referring more particularly to the pres-
55 ent invention, each splint 12 is provided with a rib-like formation 13 extending longitudinally of the splint either extending from end to end of the splint or spaced from said ends—the essential being that it be
60 present in that portion of the splint which may be exposed when the match is grasped and subjected to the igniting action, the purpose being to provide a structure which will tend to withstand the splint-breaking tend-
65 ency present at this time.

This strengthening structure may be pro-
vided in various ways, a simple construc-
tion being to produce an offset effect on a
line corresponding to the line of the desired
rib-like formation, viz:—in the direction of 70
length of the splint and intermediate its side
edges, the offset producing a rib on one side
of the splint and a depression on the other
side.

In this manner, the thickness of the splint 75
material is not materially varied—the ef-
fects of the offsetting action being the only
change in this respect—thus permitting the
effect to be produced by die action. And,
in order to reduce any tendency to weaken 80
the splint—by the group offsetting action,
this splint offsetting may be provided during
the general die operation, and, if desired,
be concurrent with or slightly in advance
of the group offsetting action of the dies. 85

The form of the splint offset employed
may be of various cross-section configura-
tion. That shown in the drawings is of a
round contour, illustrating one of the possi-
ble forms capable of being produced by 90
die action.

As will be understood, the presence of this
rib-like structure intermediate and parallel
to the side edges of the splint provides a
strengthening factor to the splint even 95
though variations in paper-board stock be
present, so that the liability of breakage—
partial or complete—of the splint is greatly
reduced. In addition, the presence of the
formation does not affect the burning quali- 100
ties of the splint itself, so that the match has
at least equal value in this respect to the
prior match structure of this type.

Furthermore, the cost of manufacture is
not materially increased—especially where 105
the splint offset is provided as a part of the
general die action, no separate handling be-
ing required.

While I have indicated various ways in
which the invention may be carried into ef- 110
fect, it will be readily understood that
changes and modifications therein may be
found desirable or essential in meeting the
exigencies of use, and I desire to be under-
stood as reserving the right to make any and 115
all such changes or modifications as may be
found necessary or desirable in so far as the
same may fall within the spirit and scope
of the invention as expressed in the accom-
panying claims when broadly construed. 120

Having thus described my invention, what
I claim as new is:

1. A match comb comprising a supporting
strip, a plurality of splints of burnable fiber
formed integral therewith each having an 125
igniting head on the outer end thereof, said
splints each having a longitudinally extend-
ing rib struck up therefrom.

2. A match comb comprising a support-
ing strip, a plurality of splints of burnable 130

fiber formed integral therewith each having an igniting head on the outer end thereof, said splints each having a longitudinal indentation forming a projecting rib.

5 3. A match comb comprising a supporting strip, a plurality of splints of paper material formed integral therewith each having an igniting head on the outer end thereof, said splints each having a longitudinal indentation forming a projecting rib.

10 4. A match comb comprising a supporting

strip, a plurality of splints of paper material formed integral therewith each having an igniting head on the outer end thereof, 15 said splints each having a longitudinal indentation forming a projecting rib, said rib extending from the point of connection of the strip and splint to the outer end thereof.

20 In testimony whereof I have hereunto set my hand.

LOUIS J. PETERS.
